RESILIENT MEANS

Julius Siebert, New York, N. Y.

Application September 29, 1934, Serial No. 746,033

2 Claims. (Cl. 155—179)

This invention relates to resilient means and refers more particularly to spring and resilient support constructions for chairs, sofas and other upholstered furniture.

5 In my co-pending patent application, Serial No. 659,248, filed March 2, 1933, an upholstered furniture construction is described, which comprises leaf springs associated with coil springs which are generally used in upholstered furniture for supporting textile coverings as well as cushions, stuffing and other material associated therewith. Such leaf springs bolster or support the fabric covering between the coil springs in order to prevent the concaving or sinking-in of the 15 covering due to which the upholstered furniture assumes a worn and dilapidated appearance and are customarily arranged in some spaced relationship between the border coil springs and the adjacent edges of the backs and seats of the 20 furniture. These leaf springs which have the shape of a U, are pivotally connected or tied to the coil springs, preferably at their opposite sides, and are rigidly or slidably connected to the skeleton of the furniture.

25 It has been found that a resilient support construction of this type can be improved to a considerable extent through an increase in the resiliency and adjustability of said springs and by the provision of members filling out the spaces between adjacent leaf springs.

An object of the present invention is the provision of resilient leaf springs for the border portions of the furniture by means of which the fabric or cushion coverings of the furniture will 35 be maintained permanently in position and will not tend to sag or sink in after a long usage.

The above and other objects of the present invention may be realized through the provision of leaf spring constructions having ends attached 40 to the furniture skeleton frame and the coil springs, the resiliency of said leaf spring construction being enhanced through the provision of a resilient slideable support for each leaf spring construction which is preferably connected to 45 the furniture skeleton. Each leaf spring construction is preferably subdivided into two or more separate resilient leaf springs which are slideable with respect to each other, whereby the circumferential length of the construction is 50 made adjustable and the resistivity of the construction against permanent deformation is increased to considerable extent. The leaf spring construction is also provided with transverse members carried by one or more leaf springs and 55 filling out the spaces between adjacent leaf spring

constructions, in order to prevent a sagging in of the furniture covering.

The invention will appear more clearly from the following detailed description when taken in connection with the accompanying drawing 5 showing preferred embodiments of the inventive idea.

In the drawing:

Figure 1 is a side view of a leaf spring construction with parts of the frame being shown 10 in section.

Figure 2 is a perspective view of the device shown in Figure 1.

Figure 3 is a perspective view of a detail of the construction shown in Fig. 1. 15

Figure 4 is a cross section through the leaf spring construction shown in Figures 1, 2 and 3.

Figure 5 shows in side elevation a leaf spring construction comprising leaf springs connected with a helical spring. 20

Figure 6 is a front detailed view of a part of the construction shown in Figure 5.

Figure 7 is a front view of a differently constructed leaf spring.

Figure 8 shows in front view a device connect- 25 ing the leaf spring to a furniture frame.

Figures 9, 10 and 11 show in perspective three different ways of connecting transverse members to the leaf spring construction.

The device shown in Figures 1, 2 and 3 of the 30 drawing comprises a furniture framework having vertical wooden structural elements 20 and horizontal wooden structural elements 21 and 22 which are connected to the elements 20. The furniture framework shown in Figure 2 may 35 form the upper part of a back or rear rest of a chair, sofa or the like.

A textile or burlap covering 23 is stretched to form the rear of the furniture piece and is connected by nails or the like with the frame ele- 40 ments 21 and 20.

A number of coil springs 24, one of which is shown in the drawing, may be sewn or otherwise suitably secured or connected to the back covering 23. 45

A plurality of leaf spring constructions 25 are employed to support the upholstery or textile covering adjacent the edges of the furniture.

As shown in Figure 1 of the drawing, each leaf spring construction 25 comprises a wire 26 50 which is tied or bent around one of the end coils of the coil spring 24 at 27. The wire 26 is firmly connected by welding or the like with one end of a bent leaf spring 28.

The opposite end of the spring 28 is inwardly 55

bent to form a rolled edge 29. The spring 28 is slidable over another bent spring 19 comprising an upper leaf spring 30 and two lower leaf springs 31 and 31a (Fig. 4), the springs 30, 31 and 31a being firmly interconnected in such manner that they form a groove the bottom of which is constituted by the inner surface of the leaf spring 30, while the edges of the groove are formed by the springs 31 and 31a, respectively. 10 The edge 32 of the spring 19 which is covered by the over-lapping portion of the spring 28 is preferably rolled or bent over.

The spring 19 is connected to the frame element 22 by means of a hinge 33 comprising a flat plate 34 which is attached by nails 35 to the frame element 22. A pivot 36 connects the plate 35 with a plate 37 which may be welded or connected by rivets 38 with the adjacent ends of the superposed leaf springs 30, 31 and 31a.

20 The leaf spring construction 25 has, consequently, the shape of a U, one leg of which is formed by the wire 26 and by the adjacent portion of the bent leaf spring 28. The other shorter leg of the U-shaped spring construction 25 is 25 formed by the hinge 33 as well as by the adjacent portion of the leaf spring 19. The intermediate interconnecting portion of the U-shaped structure is formed by the over-lapping adjacent ends of the two springs 28 and 19, as well as by the 30 adjacent portions of these two springs.

The bent spring 19 is preferably supported by a resilient wire construction 39 which is carried by the frame element 22. The device 39 comprises a coil spring 40 and a wire 41 passing through the coil 40 and having ends which are nailed to the frame element 22. The coiled wire 40 is connected with a rectangular wire member 44 which carries a slide 45 movable within the groove formed by the three leaf springs 30, 31 and 31a (Fig. 4). The end 46 of the coiled spring 40 has a shape of a bent rod bearing against the rectangular wire element 44, whereby the device 39 is caused to exert pressure upon the bent leaf spring 19, while the other end of the spring 40 45 bears against the frame.

In order to prevent the bent leaf springs 28 and 19 from separating one from the other, the adjacent ends of the two springs are held together by means of a slide 47 which is provided 50 with a middle portion 49 and two U-shaped end portions 50 surrounding the two edges of the springs 28 and 19 (Fig. 3).

As is described more fully in my co-pending patent application, Serial No. 659,248 filed March 55 2, 1933, a number of leaf spring constructions are usually arranged around the edges of a furniture structure. It has been found most advisable to fill-in the spaces between adjacent leaf spring constructions through the provision of transverse members carried by the leaf springs.

In the modification shown in Figures 1, 2 and 3 of the drawing a transverse member 51 is situated underneath the leaf spring 19. The member 51 comprises an upwardly projecting middle portion 52 which is welded or otherwise connected with the inner surfaces of the leaf springs 30, 31 and 31a. Due to this arrangement, a space is provided between the surfaces 53 and 54 of the member 51 and the adjacent edges of the leaf springs 31, and 31a, respectively, so that the bent edges 55 of the sleeve 47 (Fig. 3) can pass between the transverse member 51 and the adjacent edges of the springs 31 and 31a, thereby permitting a free relative movement between the 75 spring 28 and the spring 19.

The modification shown in Figures 5 and 6 of the drawing illustrates a framework comprising a vertical structural element 60 and a horizontal structural element 61 connected with the element 60. A covering 62 is stretched over the back of the furniture structure and is attached by nails 63 to the frame element 61. A coiled spring 64 is sewn or otherwise attached to the covering 62. The U-shaped spring structure 65 comprises a bent leaf spring 66 having an end 67 10 provided with jaws 68 clamping a portion of the end coil of the coiled spring 64 (Fig. 6).

The opposite end of the bent leaf spring 65 is 15 preferably provided with a pin 69 around which is hooked the end 70 of a coiled spring 71. The opposite end of the coil spring 71 is connected by a pin 72 or the like with a bent leaf spring 73. The spring 73 is provided with a central slot (not shown) through which passes a screw or pin 14, so that the spring 73 is slidable with respect to the member 74 and the frame element 61.

The U-shaped leaf spring construction 65 is thus formed of a bent leaf spring 66, which constitutes the longer leg of the U-shaped structure, another leaf spring 73 which constitutes the shorter leg of the U-shaped structure, and the coiled spring 71 which forms the intermediate portion interconnecting the two legs of the U-shaped structure.

20 The device illustrated in Figure 7 of the drawing comprises a leaf spring 80 having an end 81 provided with a pair of bent projecting portions 82 which have the form of hooks and which surround adjacent portions of a coil 83 forming a 35 part of a coil spring which is not shown in the drawing and which is similar to the coiled springs 24 and 64 (Figs. 1 and 5).

In this modification, the transverse members are made adjustable. The spring 80 is provided with a number of notches 84 which may be located 40 at any predetermined distance from each other and which serve the purpose of holding the slideable transverse members in certain positions upon the leaf spring 80. A transverse member 85 is carried by a part of superposed plates 86 and 88 45 which are welded or otherwise firmly connected with each other. The upper plate 86 comprises hook-shaped inwardly bent edges 87 used for holding the transverse member 85 in position. The lower plate 88 which is indicated by broken 50 lines in Figure 7 comprises bent hook-shaped end portions 89, which are situated on both sides of the leaf spring 80 and of the upper plate 86. The projections 89 engage the notches 84 and maintain the two plates 86 and 88 in position upon the 55 leaf spring 80.

It will be noted that the two superposed plates 86 and 88 form a slide having projections 87 for supporting the transverse member 85 and projections 89 holding the slide upon the leaf spring 80. 60

The transverse member 90 which may be provided with bent end portions 91 and may consist of several pieces situated on both sides of the leaf spring, is connected with the spring 80a by means of a bolt 92 passing through a longitudinal 65 slot 93 formed in the middle of the leaf spring. Due to this arrangement the transverse member 90 may be conveniently adjusted along the leaf spring 80a within the longitudinal slot 93.

The leaf spring 80a may be connected with a 70 frame element 94 of the furniture structure (Fig. 8) by means of a clip 95 which is attached at 96 to the wooden frame element 94 and which is provided with inwardly turned edges 97. Due to 75 this arrangement the edges 97 permit a longi-

tudinal movement of the leaf spring 80a while they hold said spring in position upon the frame element 94. The clip 95 may be provided with inner teeth 109 meshing with the teeth 108 of the spring 80a.

In certain instances, it may be advisable to provide the end 98 of the leaf spring 80a with a longitudinal slot 99. Then a sliding connection between the frame element 94 and the end 98 of the leaf spring 80a may be established through the provision of a bolt or tack 100 passing through the slot 99 and screwed into the frame element 94. It is possible to combine both the use of the bolt 100 and of the clip 95.

The device for supporting a transverse member which is shown in Figure 9, is substantially similar to that used for supporting the transverse member 85 (Fig. 7). The leaf spring 110 shown in Figure 9, is provided with toothed edges 111 and carries a pair of superposed plates 112 and 113 which are welded or otherwise suitably joined together. The plate 113 is provided with projections 114 overlapping the edges of the leaf spring 110. The projections 114 support the slide consisting of the two plates 112 and 113 upon the leaf spring 110.

The upper plate 112 comprises inwardly bent projections 115 forming hooks used for supporting a transverse member 116. The arrangement is substantially similar to that shown in Figure 7 with the exception that the entire edges of the leaf spring 110 are provided with teeth 111.

The modification shown in Figure 10 of the drawing comprises a slide consisting of a pair of superposed plates 120 and 121 which are welded or soldered together. The projections 122 and 123 of the upper plate 120 are joined together thereby forming a loop 124 through which a transverse flat member may be inserted. The slide is supported upon a leaf spring 125 provided with toothed edges 126, by means of wires 127 which are connected at 128 to the lower plate 121.

The slide illustrated in Figure 11 of the drawing is used for supporting a tubular transverse member 130 upon a leaf spring 131. The slide comprises a pair of U-shaped members 132 which

are bent over the edges of the leaf spring 131. Each one of the members 132 comprises a lower edge portion 133 situated underneath the leaf spring 131 and an upper edge portion 134 situated above the adjacent edge of the leaf spring 131. The two members 132 are interconnected by a web 135 bent so as to form a tube serving as a carrier for the tubular transverse member 130.

As previously described, due to the high resiliency and adjustability of the leaf spring structure and due to the provision of transverse members which may be of any desired shape and form and which may be connected in any suitable manner to the leaf spring structure, the durability of the upholstered furniture construction is increased to a considerable extent and the concaving or sinking-in of the covering is totally eliminated.

What is claimed is:

1. In an upholstered furniture construction, in combination with a frame skeleton, a covering over the rear of the frame skeleton, and a coil spring connected with said covering; a leaf spring construction comprising a leaf spring connected to said coil spring, another leaf spring connected to the frame skeleton, the two leaf springs having overlapping end portions, resilient means carried by said frame skeleton and comprising a member slidably within a groove formed in one of said leaf springs, a transverse member slidably carried by one of said leaf springs, and means for adjustably maintaining said slidable member upon said leaf spring.

2. In an upholstered furniture construction, in combination with a frame skeleton, a covering over the rear of the frame skeleton, and a coil spring connected with said covering, a leaf spring construction comprising a leaf spring connected to said coil spring, another leaf spring consisting of a plurality of leaf springs interconnected to form a longitudinal groove, the first-mentioned leaf spring and the second-mentioned leaf spring having overlapping end portions, and resilient means carried by said frame skeleton and comprising a member slidable within said groove.

JULIUS SIEBERT.
